UNITED STATES PATENT OFFICE.

ARTHUR JAMES BAZELEY, OF CLEVELAND, OHIO, ASSIGNOR, BY MESNE ASSIGNMENTS, TO NATIONAL MALLEABLE AND STEEL CASTINGS COMPANY, OF CLEVELAND, OHIO, A CORPORATION OF OHIO.

CAR COUPLER.

Application filed June 30, 1921. Serial No. 481,468.

To all whom it may concern:

Be it known that I, ARTHUR JAMES BAZELEY, a citizen of the United States, residing at Cleveland, Cuyahoga County, 5 Ohio, have invented new and useful Improvements in Car Couplers, of which the following is a specification, reference being had to the accompanying drawings, in which—

10 Fig. 1 is a vertical longitudinal section of a coupler embodying my invention; Fig. 2 is a horizontal section thereof; and Fig. 3 is a detail in plan of the lower ear of the coupler.

15 My invention relates to car couplers, and particularly to providing a coupler which not only is extremely efficient in coupling and uncoupling but is also especially designed to resist the unusual stresses of

20 modern service conditions. To this end my improved coupler has its buffing face arranged at right angles to the line of draft; depressions are formed on the knuckle co-operating with ribs on the head to protect

25 the pivot pin from strain and take up the pull; the tail of the knuckle has a projection and recess engagement with the coupler head so as to transmit the pull in draft directly to the head and not through the

30 pivot pin. In addition to the foregoing, my invention also comprises the construction and arrangement of the various features which I shall hereinafter describe and claim.

35 Referring to the drawings, A is the coupler head, B is the knuckle, C is the locking and opening piece, and D is the pivot pin for the knuckle. The lock C has a head 2 which acts as the locking piece, a depending leg 3 which acts as the opening piece, and a connecting horizontal portion 4 which extends across the knuckle tail upon which the lock normally rides.

40 The buffing faces 18 and 19 of the coupler and knuckle, respectively, as is shown in Fig. 2, are arranged at right angles to the line of draft, so as to provide for the direct application of the buffing force. Upon the knuckle and just to the rear of the pin hole

45 are the depressions 20^b, into which fit corresponding ribs 21^b on the inside of the coupler ears. The engagement of these parts with one another provides a pulling connection between the knuckle and coupler head, which assists in relieving the pivot

pin of strain. In buff the rear surfaces of the extensions 20^a contact with the surface 21^a at the rear of the ear surfaces 21. The hub surfaces 20 extend forwardly around the pin hole, terminating in the vertically disposed stop shoulders 20^c, which engage corresponding shoulders 21^c on the ears to prevent the knuckle from swinging too far outwardly. Similarly, the stop shoulders 20^d at the rear of the pin hole engage the end faces 21^d of the portions 21^b of the ears, which act as stops to limit the closing movement of the knuckle and also take up some of the buffing stresses. To prevent dirt and cinders from lodging around the hub the 65 surface 21^e immediately in front of the shoulder 21^c on the lower ear is bevelled, and that part 20^e of the depressed portion of the upper hub 20^b to the rear of the shoulder 20^c is likewise bevelled. The formation of the extensions 20^a and stop shoulders 20^d provides surfaces which bear laterally against the corresponding surfaces of the ribs 21^b in draft and serve to relieve the pivot pin of lateral strains. The tail of the knuckle has a downwardly extending lug 22, which in locked position engages an upward projection 23 on the floor of the coupler cavity, thereby serving with the extensions 20^a and ribs 21^b to transmit the 75 draft strains directly from knuckle to coupler head and relieve the pivot pin from strain.

The terms and expressions which I have employed are used as terms of description 90 and not of limitation, and I have no intention, in the use of such terms and expressions, of excluding any mechanical equivalents of the features shown and described, or portions thereof, but recognize that various 95 structural modifications are possible within the scope of the invention claimed. The arrangement of head and lock to guide and maintain the lock in the coupler head and the pivot pin support are described and claimed 100 respectively in my divisional applications Nos. 625,355 and 625,356, filed March 15, 1923.

What I claim is:

1. In a car coupler, a coupler head having 105 ears and a knuckle therebetween, the hub of the knuckle having uninterrupted hub surfaces forward of the knuckle pin when the knuckle is in open position, the hub of the knuckle also having depressions therein to 110

the rear of the pivot pin when the knuckle is in open position, shoulders on the hub of the knuckle beginning substantially at and extending outwardly from the pivot pin hole formed by said depressions, said depressions and shoulders cooperating with lugs on the coupler ears to limit the outward and inward movement of the knuckle, cooperating arc-shaped shoulders on the knuckle and ears in the region of the hub forming a pulling engagement between knuckle and ears, and in conjunction with the first named shoulders, adapted to relieve the pivot pin of lateral pressure.

15. 2. In a car coupler, a coupler head having ears and a knuckle therebetween, the hub of the knuckle having uninterrupted hub surfaces forward of the knuckle pin hole

when the knuckle is in open position, the hub of the knuckle also having depressions 20 therein to the rear of the pivot pin when the knuckle is in open position, shoulders on the hub of the knuckle beginning substantially at and extending outwardly from the pivot pin hole formed by said depressions, said depressions and shoulders cooperating with lugs on the coupler ears, an upward projection on the floor of the coupler 25 engaging a depending portion of the knuckle, said shoulders and depending portion on the knuckle cooperating with said recesses and projection on the coupler head to transmit pulling strains from knuckle to coupler and thereby relieve the pivot pin from strain.

ARTHUR JAMES BAZELEY.
